DESIGN FOR A PANEL OF EMBOSSED LEATHER

Frederick O. Merz, Philadelphia, Pa., assignor to F. O. Merz & Company, Philadelphia, Pa., a partnership

Application August 21, 1945, Serial No. 121,549

Term of patent 14 years

(Cl. D87—3)

To all whom it may concern:

Be it known that I, Frederick O. Merz, a citizen of the United States and a resident of Philadelphia, county of Philadelphia, State of Pennsylvania, have invented a new, original, and ornamental Design for a Panel of Embossed Leather, of which the following is a specification, reference being had to the accompanying drawing, forming a part thereof, wherein:

I claim:

The ornamental design for a panel of embossed leather, as shown.

FREDERICK O. MERZ.
